UNITED STATES PATENT OFFICE.

ALBERO R. HORN, OF CHICAGO, ILLINOIS.

RAILWAY-RAIL ANCHOR.

1,122,757.

Specification of Letters Patent. Patented Dec. 29, 1914.

Application filed December 13, 1913. Serial No. 803,865.

To all whom it may concern:

Be it known that I, ALBERO R. HORN, a citizen of the United States, residing at Chicago, county of Cook, State of Illinois, 5 have invented a certain new and useful Improvement in Railway-Rail Anchors, and declare the following to be a full, clear, and exact description of the same, such as will enable others skilled in the art to which it 10 pertains to make and use the same, reference being had to the accompanying drawings, which form a part of this specification.

My invention has for its object to produce a strong, simple, and efficient device which 15 may readily be attached to a railway rail, for preventing a railway rail from creeping.

The various features of novelty whereby 20 my invention is characterized will hereinafter be pointed out with particularity in the claims; but, for a full understanding of my invention and of its object and advantages, reference may be had to the following detailed description taken in connection with 25 the accompanying drawings, wherein:

Figure 1 is a transverse section taken through a railway rail adjacent to one of the ties, the rail having thereon an anchor arranged in accordance with one form of my 30 invention; Fig. 2 is a side elevation of the parts shown in Fig. 1, the tie being in section; Fig. 3 is a top plan view of the parts shown in Figs. 1 and 2; Fig. 4 is a section taken approximately on line 4—4 of Fig. 1; 35 Fig. 5 is a view similar to Fig. 1, showing a slightly modified form of anchor; and Fig. 6 is a top plan view of the parts shown in Fig. 5.

Referring to the drawings, 1 represents 40 a C-shaped member preferably in the form of a casting having strengthening ribs, 2, upon the exterior. The jaw in the member 1 is shaped to fit upon one side of the base flange of a railway rail, the lower member 45 3 being horizontal and the upper member, 4, inclined. The upper jaw member is made hollow so as to provide an internal chamber, 5, open on the side adapted to engage the top of the base flange of the rail, the chamber being closed at the ends and having its 50 top wall inclined in the direction of the length of the rail and also inclined in the transverse direction so as to make the same angle with the horizontal as the top of the 55 base flange of the rail. In the chamber 5 is a roller, 6, having a length approximately

equal to the width of the chamber and a diameter somewhat greater than the shallowest portion of the chamber.

In using the device, the roller is placed in 60 the chamber in the anchor and the latter is then slipped upon the edge of the rail base with the side at which the smaller end of the chamber is located engaging with the railway tie, the roller resting upon the top 65 of the rail base. If the rail starts to move forward, it carries the roller toward the smaller end of the chamber, wedging the roller tightly between the top of the base flange and the top wall of the chamber and 70 at the same time drawing the bottom jaw of the anchor tightly against the under side of the rail base.

In order to permit a large roller to be 75 used, I prefer to make a depression, 7, in the upper face of the lower jaw of the anchor, the depression 7 extending inwardly from the outer edge of the jaw and being large enough to receive a considerable portion of the roller. Consequently the roller 80 may be inserted in the anchor through the depression and the overlying portion of the jaw opening without limiting the diameter of the roller to the widths of the jaw opening. The depression is preferably placed just beneath the shallow end of the chamber in the anchor so that when the roller is inserted and slipped toward the large end of the chamber it cannot accidentally drop out 85 through the jaw opening.

The anchor, consisting of two simple 90 parts serves effectively to prevent creeping of the rail as long as the anchor is held in operative relation to the rail in a direction transverse of the rail. The anchor may be 95 secured in operative relation to the rail in any desired way.

In Figs. 1, 2 and 3 I have illustrated the 100 anchor as having a lateral projection or ear, 8, which is adapted to fit over the upper corner of the tie 9 and be secured thereto by a spike or other fastening means, 10.

In the arrangement shown in Figs. 5 and 105 6, the anchor is secured to the rail by means of an arm, 11, extending beneath the base, 12, of a rail and having its free end bent around the edge of the base flange opposite to that on which the anchor is located.

As I have heretofore said, any desired 110 form of holding means for the anchor may be employed since the holding means serves simply to maintain the anchor in proper

relation to the rail and does not necessarily serve as one of the elements adapted to increase the grip on the rail as the rail tends to creep.

5. I claim:

1. A device of the character described comprising a C-shaped member the lower jaw of which has a horizontal face to engage with the bottom of a rail base and the upper jaw of which has a wall inclined in the direction of the length of a rail, and a roller adapted to be placed between said wall and the top of the base flange of a rail resting on the lower jaw.
10. 2. A device of the character described comprising a C-shaped member the lower jaw of which has a horizontal upper surface to engage with the under side of a rail base, the upper jaw having a surface inclined in the transverse direction at the same angle as the upper face of the base flange of a rail and also inclined in the direction lengthwise of the rail, and a roller adapted to be arranged between the upper jaw and the top of the rail base and to contact with the rail base and with said inclined surface.
15. 3. A device of the character described comprising a C-shaped member having the lower face of the jaw horizontal and having opening out of the upper face of the jaw a chamber whose upper face is inclined

transversely to correspond to the inclination of the upper surface of the flange of a rail base and inclined in the longitudinal direction so as to make an angle with the lower horizontal face, and a roller arranged in said chamber and having a diameter less than the height of the shallow end of the chamber above the top of a rail base flange resting upon said horizontal surface.

4. A device of the character described comprising a C-shaped member having the lower face of the jaw horizontal and having opening out of the upper face of the jaw a chamber whose upper face is inclined transversely to correspond to the inclination of the upper surface of the flange of a rail base and inclined in the longitudinal direction so as to make an angle with the lower horizontal face, and a roller arranged in said chamber and having a diameter less than the height of the shallow end of the chamber above the top of a rail base flange resting upon said horizontal surface, the lower member of the jaw having a depression extending from beneath the chamber out through the edge of the jaw.

In testimony whereof, I sign this specification in the presence of two witnesses:

ALBRO R. HORN.
